BOX-FILLER CONSTRUCTION

Noel A. Petter, Los Angeles, Calif.

Application July 6, 1942, Serial No. 449,845

2 Claims. (Cl. 217—31)

This invention relates to the construction of cell type box-filters. These box-filters are composed of two sets of strips that have a configuration at their edges that enable them to be interlocked with each other by moving one set of strips transversely to the other set, both sets of strips being at the same time held in parallel relation, that is to say, one set of parallel strips is interlocked with the other set of parallel strips by lateral movement.

These box-filters are used largely in boxes so as to present a cell type of structure, that is to say, the filler presents a plurality of small cells or compartments in which small articles can be held packed, out of contact with each other, and so that they will not be damaged by shipment. Similar filler constructions are used in certain types of egg boxes.

One of the objects of the invention is to provide a correlated configuration for the interlocking edges of the two sets of strips, which will enable the cross strips that extend transversely to the other set of parallel strips, to be readily set into receiving slots or openings, and thereafter quickly moved into a position which will interlock all of the cross strips with the other strips. One set of the strips out of which these filters are constructed, is provided with openings or slots extending into one edge of the strip and provided with a throat at each opening or slot through which the cross strips are introduced in the process of interlocking them with the set of strips carrying the slots. These slots or openings are formed by means of cutting dies having knives; and one of the objects of this invention is to give the slots or openings a form which will enable the cut-out portions of the strips to be readily stripped from the bodies of the strips after the slots or openings have been cut by the dies.

Further objects of the invention will appear hereinafter.

The invention consists in the correlated configuration that I give to the interlocking edges of the parallel longitudinal strips and the parallel cross strips, and also in the method I employ for assembling and interlocking the strips, contributing to effect efficient box-filler construction.

A preferred embodiment of the invention is described in the following specification, while the broad scope of the invention is pointed out in the appended claims.

In the drawing:

Fig. 1 is a plan of a complete box-filler embodying my invention.

Fig. 2 is a vertical longitudinal cross-section through the box-filler illustrated in Fig. 1, taken in a plane parallel with one set of the strips and showing the transverse strips or cross strips al-

ready set in position by lateral movement; this view also shows dog bars and dogs for interlocking the cross strips with the other strips by another movement.

5 Fig. 3 is a section similar to Fig. 1, and showing the transverse strips in their interlocking position with the other strips.

10 Fig. 4 is a vertical section taken about on the line 4—4 of Fig. 1, that is, in a plane at right angles to the plane in which the section for Fig. 2 is taken.

15 In practicing the invention I provide a set of strips 1 of cardboard or similar material, and the individuals of this set of strips are all parallel with each other. Each of these strips is formed with equidistant openings 2 spaced along the same edge of these strips, and preferably the upper edge 3. Each opening 2 is provided with a throat 4 leading into the same from the edge 3, and this throat is disposed laterally with respect to the opening 2.

20 Furthermore, on the same side of each throat 4 throughout the length of the strip, the material of the strip is formed with an inwardly or downwardly projecting spur 5, and on the side of this strip remote from the throat 4, a shallow upwardly extending recess 6 is formed. The portion of the opening 2 opposite to the recess 6, is formed into a bottom notch 7 that constitutes a socket, as will appear hereinafter, and this notch 7 is formed by the intersection of an inclined edge 8 that extends down from the throat 4, and an inclined edge 9 that extends down from a lateral recess or notch 9 at the other side of the notch 7 and forms a portion of the bottom edge of the opening 2.

25 I also provide a second set of strips 10, and these strips are referred to as transverse strips or cross strips. Each of these strips 10 is formed with equidistant pairs of notches including a relatively large notch 11 formed at the interlocking edge of each strip which, in the present instance, is the lower edge; and a relatively shallow notch 12 that is formed in the opposite or upper edge 40 of each strip.

30 In forming the box-filler, I prefer to hold the longitudinal or main strips 1 in a parallel relation to each other with the slots or openings 2 located opposite to each other. In doing this, if desired, the lower edges of the strips may be clamped between bars 13 extending longitudinally with the strips and having upwardly projecting jaws 14 that clamp the lower edges of these strips. After this first set or main set of strips are set up in this way, I introduce the cross strips 10 into place through the throats 4 with the relatively deep notches 11 passing down until they rest on the notches or sockets 7. The notches 11 and 12 are, of course, spaced from each other by an amount equal to the distance

35 45 50 55 60 65 70 75 80 85 90 95 100

between the main strips 1 and, furthermore, the width of the material of the cross strips between the notches 11 and 12, is preferably substantially equal to the length of the edges 8 from the bottom of the notch 7 to the point where this edge intersects the edge of the throat that is remote from the spur 5. This enables all of the cross strips to lie at rest in an inclined position as indicated in Fig. 2, after they have been put in place. The cross strips 10 can then be swung into a vertical position, rotating around the socket 7 as an axis, and in doing this the bottom of each notch 12 will engage its corresponding spur 5, moving under the same and past the spur so as to come to rest in the recess or notch 6. If desired, this operation can be performed by hand; or by a machine element. In Fig. 2 I have illustrated a machine element for this purpose, involving the use of a frame having a plurality of longitudinal bars 15 extending parallel with the strips 1 and above the same, and these bars 15 may operate as dog bars having bent fingers or dogs 16 projecting down from the same and of sufficient length to engage the cross strips near their longitudinal axes; that is, considerably below their upper edges. This enables them to buckle slightly when they strike the spurs and pass under the same, and over into their vertical locking position.

The notches 7 and 12 are preferably substantially of V form.

Many other embodiments of the invention may be resorted to without departing from the spirit of the invention.

What I claim is:

1. In a box-filler construction composed of laterally interlocking strips, the combination of a first set of substantially parallel unattached strips, each strip having a plurality of equidistant openings therethrough, each of said openings having a laterally disposed throat leading into the same from the interlocking edge of the strip with a spur at the side of said throat projecting inwardly with a recess in the edge of the opening located at the side of the spur remote from the throat, said opening also having an inclined edge extending down from the throat at one side of the same and another edge cooperating with the same to produce a notch forming a socket in alignment with said recess; each of said openings having a lateral recess located between said first-named recess and said last-named notch on the same side of the throat as said spur, and a second set of freely movable unattached strips extending transversely to the

first strips having equidistant pairs of notches to cooperate with the said openings, each of said pairs of notches including a relatively deep inner notch in its interlocking edge and a relatively small notch in its outer edge, said inclined edge of the opening operating as a guide to guide the edge of the relatively deep notch of the transverse strip down into the socket so that the upper notch will rest in the throat opposite the spur and be capable of engaging the same, each of said first-named strips and its corresponding transverse strip cooperating to enable the transverse strips to be bulged laterally into the said lateral recesses, thereby enabling the outer edge of each transverse strip to move under and past the spur so as to seat in the recess back of the spur.

2. In a box-filler construction composed of laterally interlocking strips, the combination of a first set of substantially parallel unattached strips, each strip having an opening with a throat extending into the same at its upper, and interlocking, edge, each opening having a spur projecting downwardly at the side of the throat with an upwardly extending recess back of the spur, said opening also having a bottom notch located remotely from said throat out of alignment with the throat and substantially in alignment with said recess; and a set of unattached freely movable cross-strips extending transversely to the first set of strips, each of said cross-strips having equidistant pairs of notches, each pair of notches including a relatively deep substantially V-shaped notch extending up from the interlocking edge of the cross-strip, and a relatively shallow substantially V-shaped notch extending into the cross-strip from the other edge, all of said strips cooperating to enable the first set of strips to be held fixed in a substantially parallel relation with the said throats in transverse alignment so as to enable the interlocking edges of the cross-strips to be introduced through the throats with their relatively deep notches resting at the said sockets of the first set of strips, and with the relatively shallow notches located adjacent the said spurs, thereby enabling all of the cross-strips to be interlocked with the first set of strips by moving all of the cross-strips at their upper edges under and past said spurs; each of said first-named strips having a lateral recess in its said opening located on the same side of the throat as said spur, and between the said bottom notch and said recess into which the second-named strips can be bulged when interlocking the strips.
